_____*_____
Inventor.
David Merritt.*

United States Patent Office.

DAVID MERRITT, OF PHILADELPHIA, PENNSYLVANIA.

Design No. 4,408, dated October 11, 1870.

DESIGN FOR AN INKSTAND.

The Schedule referred to in these Letters Patent and making part of the same

To all whom it may concern:

Be it known that I, DAVID MERRITT, of the city and county of Philadelphia, State of Pennsylvania, have originated and designed a "Pen-Rest and Inkstand," of which the following is a full, clear, and exact description, reference being had to the accompanying drawing making a part of this specification, in which is shown a perspective view of my design.

A represents a *fac simile* of the body of the lower human jaw;

R is the ramus or branch of the jaw; and

P, the process which unites the lower jaw with the head.

The parts R and P serve to hold and act as a rest for pen-holders.

On the side and back part of the jaw are represented two wisdom-teeth, W and W', and two molar-teeth, M and M', and in the middle and at the front are represented incisor-teeth I, I¹, and I².

The upper part of the body A, between the incisors and the molars, represents the teeth removed and the openings (membranous pouches) serve to insert the ends of the pen-holders when they (the pen-holders) are not in use.

On the inner side of the body A, and immediately back of the incisor-teeth I, I¹, and I², is secured an inkstand, S.

Having thus described my design,

What I claim as my invention, and desire to secure by Letters Patent, is—

The design for pen-rest and inkstand, herein set forth.

In testimony whereof, I have hereunto signed my name in the presence of two subscribing witnesses.

DAVID MERRITT.
